COAT FRONT PAD

Daniel Bersin, New York, N. Y.

Application April 17, 1935, Serial No. 16,772

9 Claims. (Cl. 2—255)

This invention relates to the padding used for stiffening and giving form to clothing. Such padding is used to give resiliency to a garment, it helps the garment to maintain its shape. While useful for clothing in general, my invention relates especially to the pads used in the front and sides of men's coats. The padding usually consists of a piece of canvas slit and gathered to cause it to have predetermined bulges. In addition to the canvas has a layer of more resilient material such as horse-hair cloth sewed upon it to help it maintain its bulge or bulges. It has been found, however, that in the course of time, the padding loses its shape to a great extent. In order to obviate this defect, I employ a stay of flexible substantially inextensible material, such as tape, which is sewed to the pad in the form of a ring or loop in the region of the bulge. In the pad used for men's coats, one of the legs of the loop is extended beyond the ring or loop for the further purpose of causing the pad along the edge at the sleeve side to be maintained in a curl.

Other objects and advantages will become apparent upon a further study of the description and drawings, in which:

Fig. 1 is a developed elevation of a portion of the pad along the sleeve side looking at the pad from the front.

Fig. 2 is an elevation of the pad in its finished form looking at it from the front.

Fig. 3 is a cross section of the pad taken along the line 3—3 of Fig. 2.

Fig. 4 is a longitudinal section of the pad taken along the line 4—4 of Fig. 2.

Fig. 5 is a developed elevation of the horse-hair layer looking at it from the front, and

Fig. 6 is a rear view of the upper portion of the pad.

The pad shown is one suitable for use in the front and side of men's coats. Of course it will be understood my construction will apply as well to pads to be used in other parts of clothing where bulges and curls or curves are to be maintained.

The canvas layer 7 has the horse-hair layer 8 stitched to its rear at the upper portion. Behind the horse-hair layer, a layer of felt 9 is stitched which extends over a substantial portion of the canvas layer 7.

In order to form the required bulge 10, layer 7 is first slit and provided with an elongated cut-out 11 extending inward from the edge of the pad at sleeve notch 12 as seen in Fig. 1. At a substantial distance below the sleeve notch 12, a slit 13 is provided which extends inward from

the edge of the pad at the sleeve side of the pad. From about the midpoint of slit 13, an elongated cut-out 14 is located extending in a generally upward direction. A slit 17 extends downward from the upper edge between collar notch 18 and sleeve notch 12.

Horse-hair layer 8 is also provided with a cut-out 15, which when said layer is superimposed upon canvas layer 7 and stitched thereto, comes substantially opposite cut-out 11. Another cut-out 16 is also provided in horse-hair layer 8.

To give the pad its required shape, the edges of slit 17 are separated and a gore 19 is inserted and stitched therebetween. At cut-out 11, the edges are overlapped, and the edges of cut-out 15 in horse-hair layer 8 are overlapped and substantially superimposed upon the overlapped edges of cut-out 11. Said overlapped edges are then stitched to maintain them in position. The edges of cut-out 14 are overlapped as shown in Fig. 2 and stitched to maintain them in position.

The stitching and gathering of the material at the cut-outs and slits causes the pad to have a bulge 10 and a curl 20 along its edge on the sleeve side.

With the pad thus bulged and curled, a strip of flexible inextensible material or tape 21 is sewed throughout its length, preferably upon the concave side of the bulge or rear of the pad. The tape 21 is sewed in the form of a loop or ring and is located at the summit of the bulge. The area enclosed by the ring is less than the extent of the bulge. It is to be noted that the leg of the loop toward the sleeve side of the pad, extends across cut-outs 11 and 14 at intermediate points. The ring or loop formed by tape 21 is elongated with its long axis extending in an up and down direction.

From the lower end of the ring or loop formed by tape 21, one of the legs of the loop has an extension 22, which extends substantially to the edge of the pad at the sleeve side in the region of curl 20. Extension 22 tends to hold up the edge of the pad toward sleeve notch 12 thereby maintaining curl 20. Because tape 21 is substantially inextensible, and is sewed to the pad at the bulge after said bulge has already been formed, it will prevent spreading of the area encompassed by it and thereby stay or maintain the bulge.

The expression "flexible resilient piece of textile material" as used in the claims is intended to be broad enough to convey the idea that the term "piece" applies to a single layer, as layer 7,

or to several layers, such as the layers 1, 8 and 9, considered together as the piece.

I claim:—

1. A stiffening pad for clothing, comprising a flexible resilient piece of textile material having elongated cut-outs, said material being gathered at the cut-outs with the opposing edges stitched together in overlapping relation to form a bulge in said piece, and a strip of flexible substantially inextensible fabric in the form of a ring sewed to said piece at the bulge and enclosing less area than the extent of the bulge, to maintain the bulge.

2. A stiffening pad for the front of coats comprising a flexible resilient piece of textile material provided at its upper end on one side with a sleeve notch, said piece having a cut-out extending inward from the sleeve notch, and having another cut-out near the edge of the pad on the sleeve side extending upwardly from a point at a substantial distance below the sleeve notch, said material being gathered at the cut-outs with the opposing edges stitched together in overlapping relation to form a bulge in said material, and a strip of substantially inextensible textile material sewed to said piece in the form of an elongated ring with the long axis of the ring extending in an up and down direction, the side of said ring toward the sleeve side of said piece extending across said former cut-out at an intermediate point and across the latter cut-out also at an intermediate point.

3. A stiffening pad for clothing, comprising a flexible resilient piece of textile material gathered and stitched to form a bulge in said piece, and a narrow strip of flexible substantially inextensible material substantially in the form of a ring sewed to said piece along substantially the entire length of the strip within the region of the bulge to stay the bulge, said ring enclosing less area than the extent of the bulge.

4. A stiffening pad for the front of coats comprising a flexible resilient piece of textile material provided at its upper end on one side with a sleeve notch, said piece having an elongated cut-out extending inward from the sleeve notch, and having another elongated cut-out extending upwardly to a point near said former cut-out from a point at a substantial distance below the sleeve notch, said latter cut-out being near the edge of the pad on the sleeve side, said material being gathered at the cut-outs with the opposing edges stitched together in overlapping relation to form a bulge in said material, and a strip of substantially inextensible textile material sewed to said piece in the form of a ring, said ring extending across both cut-outs.

5. A stiffening pad for the front of coats comprising a flexible resilient piece of textile mate-

rial provided at its upper end on one side with a sleeve notch, said material being slit, gathered and stitched near the sleeve notch and below to form a bulge at the sleeve side of the pad and a strip of substantially inextensible flexible material sewed in the form substantially of a ring to said piece at the region of the bulge, to maintain the bulge. 5

6. A stiffening pad for the front of coats comprising a flexible resilient piece of textile material provided at its upper end on one side with a sleeve notch, said material being slit, gathered and stitched near the sleeve notch and below to form a bulge at the sleeve side of the pad and a strip of substantially inextensible textile material sewed to said piece in the form of a loop enclosing a substantial area of said bulge, one leg of the loop being longer than the other and extending from substantially the bottom of the loop outward to a point near the edge of the pad 10 on the sleeve side for holding up said edge at said point toward the sleeve notch. 15

7. A stiffening pad for the front of coats comprising a flexible resilient piece of textile material provided at its upper end on one side with a sleeve notch, said material being slit, gathered and stitched near the sleeve notch and below to form a bulge, and a tape-like strip of substantially inextensible material in the form substantially of a ring sewed at many places along its 25 length to said piece at the region of the bulge to maintain the bulge, said ring enclosing less area than the extent of the bulge. 30

8. A stiffening pad for clothing, comprising a flexible resilient piece of textile material gathered and fastened to form a bulge in said piece, and a strip of flexible substantially inextensible material in the form of a ring fastened to said piece along substantially the entire length of the strip within the region of the bulge and enclosing less area than the extent of the bulge. 35 40

9. A stiffening pad for the front of coats comprising a flexible resilient piece of textile material provided at its upper end on one side with a sleeve notch, said material being gathered and stitched near the sleeve notch and below to form a bulge in the interior of the pad near said notch and a curl at the edge of the pad below said notch, and a strip of substantially inextensible flexible material sewed to said piece in the form of a loop enclosing a substantial area of said bulge, for maintaining said bulge, one leg of the loop being longer than the other and extending from substantially the bottom of the loop outward to a point near the edge of the pad substantially at the lower end of the curl for maintaining said curl. 45 50 55
